TWO SPEED CAM SHAFT

Lawrence L. Kerby, Hermosa Beach, Calif.

Application December 4, 1956, Serial No. 626,231

6 Claims. (Cl. 123—90)

This invention relates to internal combustion engines, and more particularly to an internal combustion engine of the type having poppet valves and provided with a longitudinally adjustable cam shaft having cam elements thereon selectively engageable with the poppet valves so as to change the valve action in accordance with different loading conditions imposed on the engine.

A main object of the invention is to provide a novel and improved adjustable cam shaft system for an internal combustion engine, the system involving relatively simple parts, being easy to install, and enabling an operator to readily adjust an engine for efficient operation at different speeds.

A further object of the invention is to provide an improved internal combustion engine of the type having poppet valves mounted for reciprocation and formed and arranged to control the admission of fuel into the engine cylinders and the exhaust of products of combustion therefrom, the engine being provided with a longitudinally adjustable cam shaft having different sets of cam elements thereon selectively engageable with the poppet valves to vary the action of the valves, in accordance with different engine speeds, the engine being provided with manually controlled means for shifting the cam shaft longitudinally and being further provided with means for locking the poppet valves in elevated positions during the adjustment of the cam shaft.

A still further object of the invention is to provide an improved internal combustion engine having a longitudinally movable cam shaft, said cam shaft being provided with respective sets of cams selectively engageable with the poppet valves of the engine to establish proper valve timing for different engine speeds, the engine being provided with means for manually adjusting the cam shaft and being further provided with means acting simultaneously with the first-mentioned means for temporarily locking the poppet valves in elevated positions to allow the cam shaft to be smoothly adjusted without interference from said poppet valves.

Further objects and advantages of the invention will become apparent from the following description and claims, and from the accompanying drawings, wherein:

Figure 1 is a fragmentary longitudinal vertical cross sectional view taken through a portion of an internal combustion engine including a number of poppet valves and showing a portion of an improved multiple element cam shaft according to the present invention.

Figure 2 is an enlarged cross sectional detail view taken on the line 2—2 of Figure 1.

Figure 3 is an enlarged cross sectional view taken on the line 3—3 of Figure 2.

Figure 4 is an enlarged cross sectional detail view taken on the line 4—4 of Figure 2.

Figure 5 is a vertical transverse cross sectional view taken on the line 5—5 of Figure 1.

Figure 6 is a view showing the various elements of a fluid pressure control system employed in the present invention for controlling the adjustment of the cam shaft

2

and for providing a poppet valve locking action during said adjustment.

Figure 7 is an enlarged cross sectional view taken on the line 7—7 of Figure 6.

5 Figure 8 is an enlarged transverse vertical cross sectional view taken through the manually operated reversing valve of the system of Figure 6 on the line 8—8 of Figure 6.

Figure 9 is a fragmentary elevational view of a portion of the cam shaft shifting arm employed in the system of Figure 6 and showing the yieldable detent means employed therewith to hold the cam shaft shifting arm yieldably in an adjusted position.

Figure 10 is a cross sectional view taken on the line 10—10 of Figure 9.

15 Referring to the drawings, 11 generally designates an internal combustion engine of the type having a plurality of cylinders and having respective pairs of poppet valves 12, 13 mounted for reciprocation in the engine and formed and arranged to control the admission of fuel into the engine cylinders and to exhaust the products of combustion therefrom.

20 Designated at 14 is a cam shaft which is rotatably and slidably mounted in the engine below the poppet valves 12, 13, the cam shaft being provided with respective sets of cams 15, 16 adapted to engage the cam lifters for the respective poppet valves 12, 13, shown at 17, 18, to control the opening and closing of the fuel inlet valve 12 and the exhaust valve 13 in the proper timed sequence, the cams being suitably angularly spaced around the axis 25 of the cam shaft for the different sets of valves 12, 13 for the respective cylinders, in a manner well known in the art.

25 As shown in Figures 1, 2 and 4, each valve is provided with a cam lifter element 17 or 18, the lifter 18 being illustrated in Figure 2, each lifter comprising a cylindrical block 19 slidably mounted for reciprocation in a bore 20 formed in the engine block and biased downwardly toward its associated cam by a coiled spring 21 surrounding the shank of the associated valve and bearing 30 between the top wall of bore 20 and the cylindrical block 19. Each cam lifter block is held against rotation by the provision of a vertical groove 22 formed in its bore 20 in which is slidably engaged a pin 23 secured in the block and projecting radially therefrom. Opposite the pin 23, the lifter block is formed with an arcuate groove 24 adapted to receive the end of a locking pin 25 when the block is in an elevated position, as will be presently described, whereby the valve lifter may be held in a position wherein it will not interfere with cam shaft 35 14 when the cam shaft is shifted.

35 The cam shaft 14 is formed adjacent the respective cams 15 and 16 with additional cams 15' and 16' adapted to engage the cam lifters 17 and 18 when the cam shaft is shifted longitudinally to provide a modified valve action and thus to provide a different type of engine performance. Thus, when the cams 15 and 16 act on the lifters 17 and 18, the engine may provide performance suitable for low or moderate speeds, such as under city traffic conditions. When the cams 15' and 16' are employed to act on the lifters 17 and 18, the engine performance may be that required for high speed or heavy loading conditions, such as for climbing steep hills or for operating the associated motor vehicle at high speeds.

40 Cam shaft 14 is driven from the engine crank shaft in any suitable manner, for example, by the provision of a drive shaft 26 coupled to the engine crank shaft, said drive shaft being provided with a pinion gear 27 meshing with a larger gear 28 rotatably supported in the engine in any suitable manner and splined to the cam shaft by the provision of a splined portion 30 on the cam shaft 45 which slidably engages through a correspondingly splined central aperture in the gear 28. The splined cam shaft 50

portion 30 also drives a worm gear 31 which is in turn coupled to the distributor worm shaft 32, whereby the engine distributor 33 is driven synchronously with the cam shaft 14.

Secured to the end of the splined portion 30 externally of the engine block is an inner bearing ring 34, said inner bearing ring being mounted on the reduced shaft end portion 35, as shown in Figure 1, being secured thereon by a nut 36 threaded on said reduced end portion and clampingly engaging the ring.

The bearing ring 34 is rotatably mounted within an outer bearing ring 37, being journaled thereto by ball bearings 38 positioned in opposing annular raceways formed in the bearing rings 34 and 37, providing an anti-friction connection between the ring 37 and the cam shaft 14. A yoke member 39 is pivoted to the outer ring 37, as by diametrically opposite pivot pins 40, 40 rotatably connecting the arms of yoke member 39 to diametrically opposite portions of the outer bearing ring 37, as shown in Figures 1 and 5. The yoke 39 is rigidly secured to the end of an arm 41 pivoted in any suitable manner to the vehicle frame for rotation around an axis spaced from and perpendicular to the axis of the cam shaft, whereby rotation of arm 41 shifts the cam shaft longitudinally.

Connected to the arm 41, as by a collar member 42 is a shift arm 43, which may be actuated in any suitable manner, for example, by fluid pressure means, as will be presently described, for shifting the cam shaft 14.

Mounted in the engine block 11 perpendicular to and adjacent each valve lifter is a horizontal sleeve member 44 in which the associated locking pin 25 is axially positioned. As shown in Figure 2, each locking pin 25 is carried on a circular piston element 46 slidably engaged in the associated sleeve 44, each pin having a shank portion 47 projecting into an auxiliary cylinder member 48 provided in the sleeve 44, each shank element 47 having a head portion 49 slidably engaged in the associated auxiliary cylinder 48. Each cylinder 48 is rigidly secured to an annular ring member 50 which surrounds the associated shank 47 and which is slidably supported in the associated sleeve 44.

A first coiled spring 51 surrounds the pin 25, bearing between the piston element 46 and the opposing wall of the bore of the engine block, biasing the pin member away from its associated valve lifter, namely, in a direction to the left, as viewed in Figure 2. A second coiled spring 52 surrounds the shank 47, bearing between the associated piston 46 and the annular ring member 50, serving to transmit the force of spring 51 to the auxiliary cylinder 48. The central aperture of ring 50 is substantially smaller than the diameter of the head 49, whereby movement of the ring member 50 to the left, as viewed in Figure 2, will urge the head 49 to the left, and will act to withdraw the pin 25 from the arcuate notch 24 of its associated valve lifter when there is no opposing force applied to the associated auxiliary cylinder 48.

Axially secured to each auxiliary cylinder 48 is a rack bar 54 which meshingly engages with an associated pinion gear 56 secured on a shaft 57 rotatably mounted, in any suitable manner, and supported on the engine 11.

As will be apparent from Figure 2, when the shaft 57 rotates clockwise, as viewed in Figure 2, the rack gear 54 is urged to the right, whereby the auxiliary cylinder 48 exerts a force on the annular ring member 50, which is transmitted by spring 52 to piston member 46, whereby the locking pin 25 is urged to the right, as viewed in Figure 2, and will enter the annular groove 24 in the associated valve lifter when said valve lifter is elevated, for example, to its uppermost position shown in Figure 2, and will be maintained in elevated position as long as the clockwise torque continues on shaft 57.

It will be understood that each of the valve lifters 17 and 18 associated with the various poppet valves of the engine is provided with means such as is illustrated in

Figure 2, including a locking pin 25, adapted to lockingly engage with the associated valve lifter to retain the valve lifter in its elevated position, substantially clear of the cam shaft, when its associated rack bar 54 is moved inwardly by the clockwise rotation of shaft 57, said shaft 57 acting simultaneously on all the rack bars, so that the locking action is simultaneously provided on all the valve lifters.

It will be understood that the grooves 24 are located so that the pins 25 can only enter said grooves when the associated valve lifter blocks have been elevated to their highest positions by the respective cams on the cam shaft. Thus, when it is desired to shift the cam shaft, by rotating the pivoted arm 41 by means of its actuating bar 43, torque is applied to the shaft 57, to simultaneously urge the respective locking pins 25 inwardly toward their associated valve lifter blocks 19, and the valve lifter blocks will become locked in their elevated positions sequentially as they reach such positions responsive to the action of their associated cams. The valve lifter blocks will be subsequently maintained elevated, allowing the cam shaft to be freely shifted until the torque is removed from the shaft 57, whereby the springs 51 will act to retract the locking pins 25 from the grooves 24 and will release the valve lifters for cooperation with the new set of cams.

Referring now to Figures 6 to 10, a typical installation is disclosed, for example, in a motor vehicle, the shaft 57 being shown as journaled in brackets 58, 58 and being provided with a pinion gear 59, which is engaged by a rack bar 60. The rack bar 60 is carried on a piston rod 61 which extends from a piston 62 mounted in a fluid pressure cylinder 63. Cylinder 63 is suitably mounted on the vehicle frame and has connected to its top end a conduit 64 leading from the discharge end of a main cylinder 65. Cylinder 65 is provided with a piston 66 slidably mounted in a chamber 67, the piston being provided with the piston rod 68 which is connected by a link bar 69 to the depending arm 70 of a bell crank 71. Bell crank 71 is provided with the upper arm 72 formed at its end with the upwardly extending foot pedal portion 73 passing through an aperture 74 in the vehicle floorboard and provided at its top end with a pedal 75. Bell crank 71 may be biased counterclockwise, as viewed in Figure 6, in any suitable manner, for example, by the provision of a biasing spring 76 connecting arm 72 to the vehicle floorboard, as shown, whereby the piston 66 is biased to the right, as viewed in Figure 6, and will be moved to the right when the pedal 75 is released.

The main cylinder 65 is provided with the upper reservoir portion 77, and communicates with the chamber 67 by the provision of an aperture 78 adjacent the right end of main cylinder 65, as viewed in Figure 6.

Designated at 79 is a control valve, comprising a cylindrical body 80 in which is rotatably mounted a sector-shaped rotor 81, said rotor being provided with the external actuating shaft 82 centrally secured to the operating disc 83. The operating disc 83 may be rotated in any suitable manner, for example, by a link bar 84 connected to a suitable manual control element, for example, a lever located adjacent the operator of the vehicle.

The valve 79 is of the duplex two-way type, comprising a first set of ports 85 and 86 located adjacent one end of cylinder 80 and angularly spaced by an amount slightly less than the angle subtended by the sector member 81, whereby port 85 may be selectively placed in communication either with port 86 or with a bottom port 88 provided in the cylindrical body 80.

An additional pair of ports 89 and 90 are provided in body 80, longitudinally aligned with the respective ports 85 and 86, and located adjacent the opposite end of the body 80, the port 89 being adapted to be selectively placed in communication with port 90 or with a bottom port 91 provided in the cylindrical valve body 80 in longitudinal alignment with the bottom port 88.

The cam shaft shift arm 43 is connected to a piston 93 slidably mounted in a fluid pressure cylinder 94 suitably mounted on the vehicle frame. The right end of cylinder 94, as viewed in Figure 6, is connected by a conduit 95 to port 90 of valve 79 and is further connected by a conduit 96 to the bottom port 88 at the left end of the cylindrical body 80 of the valve 79. The left end of the cylinder 94 is connected to port 86 by a conduit 97 and is further connected to bottom port 91 by a conduit 98.

Normally, the valve control disc 83 is in a neutral position, as shown in Figure 8, wherein the respective ports 85, 86, and 89, 90 are covered. Assuming that it is desired to shift the cam shaft 14 to the right, as viewed in Figure 1, namely, in a direction to substitute the cams 16' and 15' for the cams 16 and 15, the locking control arm 84 is moved in a direction to place ports 89 and 85 in communication with bottom ports 91 and 88, namely, to rotate the valve rotor 81 clockwise, as viewed in Figure 8. Foot pressure is then applied to the pedal 75, causing the piston 66 to force fluid through conduit 64 into the top end of cylinder 63, moving the piston 62 downwardly. Downward motion of piston 62 causes rack bar 60 to rotate pinion 59 and to thus rotate the valve lifter locking shaft 57 in a direction to rotate the associated pinions 56 clockwise, as viewed in Figure 2 and to move the rack bar 54 associated therewith inwardly toward their associated valve lifters 19. The valve lifters become locked in elevated positions, by the pins 25 in the manner above described, and ultimately, with continued foot pressure applied to pedal 75, the piston 62 moves to the lower portion of cylinder 63 allowing the fluid to escape therefrom through a conduit 99 connecting the portion of cylinder 63 just above the lowermost position of piston 62 to the valve port 89. The fluid under pressure then passes through conduit 98 into cylinder 94 and acts on piston 93 to move the shift arm 43 to the right, as viewed in Figure 6, and also to move cam shaft 14 to the right as viewed in Figure 1, causing the cam shaft to be shifted longitudinally to bring cams 16' and 15' beneath the valve lifters 18 and 17. Fluid discharges from the right end of cylinder 94 through conduit 96 into the body of valve 79 and thence through port 85 and a conduit 100 connected thereto to the reservoir 77 of the main cylinder 65. When the foot pressure applied to the pedal 75 is released, coiled spring 76 acts to elevate the pedal and also acts to return piston 66 to the right end of chamber 67. The springs 51 act to retract the locking pins 25 from the grooves 24 and to extend the rack bars 54, causing the pinion 56 to rotate the shaft 57 counterclockwise, as viewed in Figure 2. This elevates the rack bar 60 and causes the piston 62 to return to its normal, elevated position in cylinder 63. Shift arm 43 tends to remain in its adjusted position, since conduit 99 is closed off by the elevation of the piston 62 and there is no further force acting on the piston 93.

The bottom of cylinder 63 is connected to the fluid return line 100 by a conduit 120 to allow fluid to return to reservoir 77 when piston 62 descends.

Preferably, releasable retaining means is provided for retaining the shift arm 43 in adjusted position. Thus, the shift arm 43 may have rigidly secured thereto a block member 101, at an intermediate portion of the shift arm 43, the block member 101 extending slidably through a bracket member 102 secured to the vehicle frame, said bracket member including an arm 103 transversely overlying the block member 101. The arm 103 is formed with a recess in its intermediate portion, shown at 104, in which is mounted a coiled spring 105 acting on a ball detent 106 of conventional structure, the ball detent being selectively engageable in a pair of spaced recesses 107 and 108 formed in the block 101, and corresponding to the two different positions of adjustment of the shift arm 43, namely, a first position wherein the cams 15 and 16 are located beneath the valve lifts 17 and 18, and a sec-

ond position wherein the cams 15' and 16' are located beneath the valve lifters 17 and 18.

The block member 101 is supported for sliding movement with respect to the bracket member 102 in any suitable manner, for example, by respective sets of link bars 110, 111 loosely connected to the opposite end portions of the block member 101, as by pins 112, and pivoted respectively to the top and bottom corner portions of the bracket member 102 by pivot pins shown respectively at 10 113 and 114.

After the shift arm 43 has been moved to its selected position, in the manner above described, the valve 79 is returned to its neutral position by rotating the control disc 83 to move the sector-shaped valve body 81 to its 15 neutral position, shown in Figure 8.

When it is desired to reverse the operation above described, namely, to return the shift arm 43 to its initial position, wherein cams 15 and 16 are positioned below lifter members 17 and 18, the same procedure above described is employed except that the disc 83 is rotated in a direction to block off the bottom ports 91 and 88 and to connect port 89 to port 90 and port 85 to port 86. Thus, when piston 62 descends, the fluid under pressure from cylinder 63 passes through conduit 99 and through ports 89 and 90 to conduit 95, entering the right end of cylinder 94 and exerting force on piston 93 to move shift arm 43 to the left. Fluid from the forward end of cylinder 94 discharges through conduit 97 and through ports 86 and 85 to the return conduit 100, being thus returned to 20 the reservoir 77. Previous to this, the same valve lifter locking action previously described occurs, since shaft 57 is rotated by the downward movement of the piston 62 caused by depression of the pedal 75.

It will be understood that the duplex two-way valve 79 35 comprises two separate chambers 113' and 114', the chamber 113' containing the ports 85, 86 and 88 and the chamber 114' containing the ports 89, 90 and 91.

While a specific embodiment of an improved cam shaft shifting means for an internal combustion engine has 40 been disclosed in the foregoing description, it will be understood that various modifications within the spirit of the invention may occur to those skilled in the art. Therefore, it is intended that no limitations be placed on the invention except as defined by the scope of the appended claims:

What is claimed is:

1. In an internal combustion engine, poppet valves mounted for reciprocation and formed and arranged to control the admission of fuel into the engine cylinders 50 and the exhaust of products of combustion therefrom, a cam shaft rotatably and slidably mounted in the engine beneath the valves and having at least two cams selectively movable beneath each poppet valve responsive to longitudinal movement of the cam shaft, spring means biasing the poppet valves into engagement with said cam shaft, respective locking pins slidably mounted in the engine adjacent to and perpendicular to the valves, said valves being formed with respective recesses located to receive said pins when the valves are elevated substantially to their uppermost positions, means for adjusting said cam shaft longitudinally, means urging said pins away from said valves, and manually operated means formed and arranged to simultaneously move said pins toward engagement with said valves for entry into said recesses and to releasably lock the poppet valves in elevated positions during the longitudinal adjustment of the cam shaft.

2. In an internal combustion engine, poppet valves mounted for reciprocation and formed and arranged to control the admission of fuel into the engine cylinders and the exhaust of products of combustion therefrom, a cam shaft rotatably and slidably mounted in the engine beneath the valves and having at least two cams selectively movable beneath each poppet valve responsive to longitudinal movement of the cam shaft, spring means

biasing the poppet valves into engagement with said cam shaft, respective locking pins slidably mounted in the engine adjacent to and perpendicular to the valves, said valves being formed with respective recesses located to receive said pins when the valves are elevated substantially to their uppermost positions, spring means biasing said pins away from said recesses, means for adjusting said cam shaft longitudinally and manually operated means formed and arranged to simultaneously move said pins toward engagement with said valves for entry into said recesses against the force of said last-named spring means to releasably lock the poppet valves in elevated positions during the longitudinal adjustment of the cam shaft.

3. In an internal combustion engine, poppet valves mounted for reciprocation and formed and arranged to control the admission of fuel into the engine cylinders and the exhaust of products of combustion therefrom, a cam shaft rotatably and slidably mounted in the engine beneath the valves and having at least two cams selectively movable beneath each poppet valve responsive to longitudinal movement of the cam shaft, spring means biasing the poppet valves into engagement with said cam shaft, respective locking pins slidably mounted in the engine adjacent to and perpendicular to the valves, said valves being formed with respective recesses located to receive said pins when the valves are elevated substantially to their uppermost positions, spring means biasing said pins away from said recesses, means for adjusting said cam shaft longitudinally, spring means biasing said pins away from said recesses, respective rack bars axially connected to said pins, a shaft rotatably mounted adjacent said rack bars, pinion gear means on said last-named shaft meshing with said rack bars, and means formed and arranged to rotate said last-named shaft in a direction to simultaneously move said pins toward engagement with said valves for entry into said recesses against the force of said last-named spring means to releasably lock the poppet valves in elevated positions during the longitudinal adjustment of the cam shaft.

4. In an internal combustion engine, poppet valves mounted for reciprocation and formed and arranged to control the admission of fuel into the engine cylinders and the exhaust of products of combustion therefrom, a cam shaft rotatably and slidably mounted in the engine beneath the valve and having at least two cams selectively movable beneath each poppet valve responsive to longitudinal movement of the cam shaft, spring means biasing the poppet valves into engagement with said cam shaft, respective locking pins slidably mounted in the engine perpendicular to the valves, said valves being formed with respective recesses located to receive said pins when the valves are elevated substantially to their uppermost positions, fluid pressure-operated means formed and arranged to adjust said cam shaft longitudinally, spring means biasing said pins away from said recesses, respective rack bars axially connected to said pins, a shaft rotatably mounted adjacent said rack bars, pinion gear means on said last-named shaft meshing with said rack bars, and means controlled by said fluid pressure-operated means and formed and arranged to rotate said last-named shaft in a direction to simultaneously move said pins toward engagement with said valves for entry into said recesses against the force of said last-named spring means to releasably lock the poppet valves in elevated positions during the longitudinal adjustment of the cam shaft.

5. In an internal combustion engine, a plurality of poppet valves mounted for reciprocation and formed and arranged to control the admission of fuel into the engine cylinders and the exhaust of products of combustion therefrom, a cam shaft rotatably and slidably mounted in the engine and having at least two cams selectively movable beneath each poppet valve responsive to longitudinal movement of the cam shaft, means biasing the poppet valves into engagement with the cam shaft, respective locking pins slidably mounted in the engine perpendicular to the valves, said valves being formed with locking recesses located to receive said pins when the valves are elevated substantially to their uppermost positions, spring means biasing said pins away from the recesses, respective rack bars axially connected to the pins, a shaft rotatably mounted adjacent said rack bars, pinion gear means on said last-named shaft meshing with said rack bars, a rotary control arm coupled to said cam shaft, fluid pressure means operatively connected to said control arm formed and arranged to rotate said control arm and to shift said cam shaft longitudinally, and further fluid pressure-operated means formed and arranged to rotate said last-named shaft against the force of said spring means simultaneously with the operation of said first-named fluid pressure means, whereby to move said pins simultaneously toward said valves for entry into said recesses to releasably lock said poppet valves in elevated positions during the longitudinal adjustment of the cam shaft.

30 6. In an internal combustion engine, a plurality of poppet valves mounted for reciprocation and formed and arranged to control the admission of fuel into the engine cylinders and the exhaust of products of combustion therefrom, a cam shaft rotatably and slidably mounted in the engine and having at least two cams selectively movable beneath each poppet valve responsive to the longitudinal movement of the cam shaft, means biasing the poppet valves into engagement with the cam shaft, respective locking pins slidably mounted in the engine perpendicular to the valves, said valves being formed with locking recesses located to receive said pins when the valves are elevated substantially to their uppermost positions, spring means biasing said pins away from the recesses, respective rack bars axially connected to the pins, a shaft rotatably mounted adjacent said rack bars, pinion gear means on said last-named shaft meshing with said rack bars, a rotary control arm coupled to said cam shaft, fluid pressure means operatively connected to said control arm formed and arranged to rotate said control arm and to shift said cam shaft longitudinally, further fluid pressure-operated means formed and arranged to rotate said last-named shaft against the force of said spring means simultaneously with the operation of said first-named fluid pressure means, whereby to move said pins simultaneously toward said valves for entry into said recesses to releasably lock said poppet valves in elevated positions during the longitudinal adjustment of the cam shaft, and yieldable detent means engaging said control arm and yieldably holding said control arm in adjusted position.
